UNITED STATES PATENT OFFICE.

ANDREW C. JAMES, OF HOUSTON, TEXAS.

ELECTRODE HOLDER.

Application filed May 21, 1927. Serial No. 193,150.

This invention relates to new and useful improvements in an electrode holder.

One object of the invention is to provide an implement of the character described 5 specially designed for the purpose of holding an electrode to be used in electric welding and the invention comprehends an implement whereby the electrode may be securely held while in use and may be readily 10 released.

Another object of the invention resides in the provision of an implement of the character described which may be easily handled in applying an electrode to the work.

15 A still further feature of the invention resides in the provision of an electrode holder which is of very simple construction and may be cheaply and easily produced.

With the above and other objects in view the invention has particular relation to certain novel features of construction, operation and arrangement of parts, an example of which is given in this specification and illustrated in the accompanying drawings, wherein:—

Figure 1 shows a side elevation of the implement shown partly in section.

Figure 2 shows a side elevation thereof, partly in section, taken at right angles to the view shown in Figure 1.

Figure 3 shows a transverse sectional view of the implement, taken on the line 3—3 of Figure 1, and

Figure 4 shows an end view thereof.

Referring now more particularly to the drawings, wherein like numerals of reference designate similar parts in each of the figures the numeral 1 designates a tubular handle or grip member formed of suitable insulating material. Fastened to one end of the handle there is a guard 2, preferably circular in contour and also formed of insulating material. Fastened to the guard end of the handle there is a tubular shank 4 whose outer end carries a suitable bracket 5 which terminates in the overturned fixed jaw 6. In the grip 1 there is a U-shaped bracket 7 which is preferably secured to the grip by means of a suitable set screw 8 and whose ends 9 and 10 are overturned into alignment and the latter of which is formed with a bearing 11. A U-shaped clamp 12 is fitted over the overturned end 9 and secured thereto by means of a set screw 13 which passes through said clamp as well as through the overturned end 9 and the side

arms 14 of said clamp are overturned and embrace the end 9 so as to prevent the clamp 12 from turning or pivoting on the set screw 13. An electrical conductor 15, forming one side of the electrical circuit has its inner end clamped between the clamp 12 and the overturned end 9. There is a lever 16, one end of which is pivoted to the bracket 7 and whose other end projects through an elongated slot 17 in the handle 1, said projecting end being formed with a thumb plate 18 by means of which the lever may be moved.

A stem 19 has a pivotal connection to the lever 16 and works through the shank 4 and its outer end is provided with a movable jaw 20. There is a coil spring 21 interposed between the overturned end 9 and the lever 16 and whose respective ends surround the opposing ends of the screw 13 and the rod 19 respectively by means of which said spring is retained against displacement. 70 75

One end of the electrode 22 to be held may be inserted between the jaws 20 and 6 and when making this insertion the lever 16 should be depressed to draw the movable jaw from the fixed jaw and when released the pressure of the spring 21 will operate to move the movable jaw 20 into clamping relation with the electrode. The electrode may then be brought into operating relation with the work, the latter forming the other side of the electrical circuit. 80 85

While I have illustrated one form of the implement, which I now consider the preferred form thereof it is obvious that mechanical changes may be made and equivalents substituted for the parts shown and I reserve the right to make such changes as may be found desirable so long as I keep within the scope of the appended claims. 95

What I claim is:—

1. An implement of the character described including a tubular handle, a plate like guard fixed to said handle, a tubular shank attached to the handle at one end, a bracket fixed to the other end of said shank which terminates in an overturned fixed jaw, a U-shaped bracket in said handle whose ends are overturned into alignment one of said ends being formed with a bearing, a U-shaped clamp fitted over the other overturned end and having side arms which clamp said end, a lever, one end of which is pivoted to the bracket in said handle and whose other end works through an elong-

gated slot in said handle, a stem working through said bearing and handle and whose other end is provided with a movable jaw and a coil spring operable against said lever 5 and normally tending to hold movable jaw in cooperating relation with the fixed jaw.

2. An implement of the character described including a tubular handle, a plate like guard fixed to one end of said handle, 10 a tubular shank attached to the guard end of the handle, an overturned fixed jaw carried by the free end of the shank, a U-shaped bracket in the handle whose ends are overturned into alignment one of said ends being 15 formed with a bearing, a U-shaped clamp

fitted over the other end of said bracket and having side arms which clamp said bracket end, means for securing said clamp to said end, said handle having a slot, a lever pivoted to said bracket and working through 20 said slot, a stem working through said bearing and shank, a movable jaw fixed to said stem and confronting said fixed jaw, said stem being pivotally connected to said lever and a yieldable member interposed between 25 said bracket and lever.

In testimony whereof I have signed my name to this specification.

ANDREW C. JAMES.
